UNITED STATES PATENT OFFICE

2,416,959

EDUCATIONAL TOY

Jacob Herzl Segal, Chicago, Ill., assignor to Etron
Industries, Inc., a corporation of Illinois

Application October 12, 1945, Serial No. 621,969

7 Claims. (Cl. 35—22)

1

The present invention relates to educational toys of the type comprising a block (usually of wood) containing a plurality of recesses adapted to receive correspondingly shaped pegs or other insertable elements. These toys are intended to teach very young children coordination of mind and muscle through selection of an element and insertion in the proper recess. The recesses and elements are so constructed as to preclude interchangeability.

It is the object of this invention to provide an educational toy of the type described which has greater initial appeal to children than the conventional toy and is more effective in sustaining the interest of the child. In general, I incorporate in the toy a battery, an electric lamp and means for causing the lamp to light when the elements are inserted in the correct recesses. The flash of light is a fascinating reward to young children for successful completion of the comparatively simple operation they are called upon to perform. A bell or buzzer may be used instead of a light. Other more specific objects will appear upon reading the following specification and claims and upon referring to the annexed drawings to which they relate.

In the drawings in which a preferred embodiment of the present invention is disclosed:

Fig. 1 discloses a perspective view of the toy with the triangular element in place;

Fig. 2 is a section upon the line 2—2 of Fig. 1;

Fig. 3 depicts a top plan view of the lower member of the block with the upper member removed; and

Fig. 4 is a bottom plan view of the upper member of the block.

The same reference characters designate the same parts in all the figures.

The block 1 is preferably of a dielectric material such as wood, plastic and the like to avoid the necessity of insulating the various electro-conductive elements. The block 1 is most conveniently constructed of a lower member 1a and an upper member 1b which are joined by screws, glue or other suitable means to form one integral block after the elements comprising the electrical circuit have been installed. The upper member 1b contains holes 4 preferably differently shaped which appear as recesses when the two members 1a and 1b are joined. These recesses 4 receive correspondingly shaped elements 5, of which only the triangular shaped one is shown in the drawings.

On the underside of the upper member 1b, there is mounted, by means of screws 18, a clover-

2

leaf shaped switch 6, made of conductive resilient material adapted to withstand repeated flexing. The switch 6, is preferably of such shape and size as to cover completely the recesses 4, and being flush with the underside of the upper member 1a, gives the appearance, when viewed from the top, of being the bottom of the recess. This effect is accentuated by enameling the upper member 1b and the topside of the switch 6 the same color.

10 The upper member 1b contains also a centrally located hole 7 to accommodate a socket 8 and an electric lamp 9. One terminal bracket 8a of the socket 8 is fastened to the switch 6. The other terminal bracket 8b of the socket 8 extends into another recess 10 of the upper member which accommodates a dry cell battery 11, one terminal of which contacts the socket bracket 8b. A plate 12, preferably of translucent plastic covers the socket hole 7 and the battery recess 10. The plate 12 may also be of opaque material providing that the portion covering the socket hole 7 be perforated to permit the light from the lamp 9 to shine through the plate 12. The plate 12 is fastened to the upper member 1b with screws 13 or other means permitting removal of the plate 12 for the purpose of replacing a worn out light bulb or battery.

15 The lower member 1a of the block 1 is gouged out to form a recess 14. In this recess 14 a metallic contact ring 15 is fastened with staples 16 or other suitable means. The contact ring 15 preferably has a coiled terminal 17 of sufficient diameter to accommodate and contact one end of the battery 11. The recess 14 is of sufficient depth so that when the two members 1a and 1b of the block 1 are joined a clearance will exist between the contact ring 15 and the under side of the switch 6. When the element 5 is inserted in the recess 4 and pressed down, the under side of the switch 6 contacts the staple 16 completes the circuit and causes the lamp to light. When the pressure is withdrawn the switch 6 springs back to its position flush with the underside of the upper member 1b breaking the circuit. The switch 6 preferably is of such resiliency that the weight of the peg 4 itself is not sufficient to force it down to establish contact, otherwise the mere insertion of the element 5 would cause the lamp to remain lit and unnecessarily drain the battery. The disclosed construction results in prolonging the life of the battery because the child intermittently flashes the light by exerting pressure when the element 5 is inserted.

20 Many variations in construction are of course

possible without affecting the basic operation of the toy. For example, the hole for the battery may be eliminated and a recess on the underside of the upper member or on the top side of the lower member of the block may be substituted. In this event it will be necessary to separate the two members of the block when the battery is replenished. This construction has the advantage of eliminating the need for the plate 12 and requires only a simple cup shaped shield to cover the light bulb. The means for closing the circuit may also be varied in many ways. For example, a second contact ring may be positioned parallel to contact ring 15 and the terminal bracket 8a of the socket 8 is connected with the second contact ring. In such case the circuit is closed by pressing the switch across both contact rings. Alternatively the switch may be mounted up on the lower member of the block so as to contact the second ring but clear the contact ring 15. In such case the circuit is closed by pressing the switch downward to touch contact ring 15. Other variations in construction will readily occur to skilled workers in the art.

While I have described a preferred embodiment it will be understood that this is to be taken as illustrative and not limitative of my invention and that I reserve the right to make various changes in form, construction and arrangement of parts without departing from the spirit and scope of my invention as set forth in the following claims:

I claim:

1. In an educational toy of the type comprising a block containing dissimilarly sized and shaped recesses adapted to accommodate selectively correspondingly dissimilarly sized and shaped elements, the combination with said block and elements of an electrically operated signal device, means for energizing said signal device, an open circuit between said energizing means and said signal device and a circuit closing switch controllable by pressure exerted through said elements inserted in said recesses.

2. In an educational toy of the type comprising a block containing dissimilarly sized and shaped recesses adapted to receive selectively correspondingly dissimilarly sized and shaped elements, the combination with said block and elements of a dry cell battery, an incandescent lamp, an open circuit between said battery and said lamp and means for closing said circuit by pressure exerted upon any of said elements inserted in its corresponding recess.

3. In an educational toy of the type comprising a block containing dissimilarly sized and shaped recesses adapted to receive selectively correspondingly dissimilarly sized and shaped elements, the combination of a block composed of a plurality of members forming an internal compartment, a dry cell battery, an incandescent lamp, an open circuit between said battery and said lamp, a switch mounted on the roof of said compartment and a contact member positioned on the floor of said compartment, said circuit being closable by pressing said switch against

said contact member upon the insertion under pressure of an element in a corresponding recess.

4. In an educational toy of the type comprising a block containing dissimilarly sized and shaped recesses adapted to receive selectively correspondingly dissimilarly sized and shaped elements, the combination of a block containing an internal compartment, a dry cell battery, an incandescent lamp, an open circuit between said battery and said lamp, a flexible switch mounted on the roof of said compartment, said switch being of sufficient size to form a complete bottom for each of said recesses, and a contact member positioned on the floor of said compartment, said circuit being closed when said switch is pressed against said contact member by the insertion of an element in its corresponding recess.

5. In an educational toy of the type comprising a block containing dissimilarly sized and shaped recesses adapted to receive selectively correspondingly dissimilarly sized and shaped elements, the combination of a block containing an internal compartment, a dry cell battery, an incandescent lamp, an open circuit between said battery and said lamp, a flexible pressure operated switch mounted on the floor of said compartment and a contact member mounted spacedly from said switch and adapted to be contacted thereby when said switch is pressed downwardly to close said circuit by the insertion of an element in its corresponding recess.

6. A toy comprising a body containing a plurality of recesses of predetermined dissimilar sizes and shapes, elements having sizes and shapes complementing portions of certain of said recesses respectively, signal means cooperating with said elements and recesses, and means for operating said signal means sensitive to the insertion of said elements in said certain of said recesses under pressure, but insensitive to mere insertion of said elements therein.

7. A toy comprising a body containing a plurality of recesses of predetermined dissimilar sizes and shapes, elements having sizes and shapes complementing portions of certain of said recesses respectively, electric signal means cooperating with said elements and recesses, a circuit including said signal means and switch means for operating said signal means sensitive to the insertion of said elements in said certain of said recesses under pressure, but insensitive to mere insertion of said elements therein.
